STRAIGHT KNITTING MACHINE YARN
CARRIER CONTROL MECHANISMChristian F. Meyer, Wyomissing, Pa., assignor to
Textile Machine Works, Wyomissing, Pa., a cor-
poration of Pennsylvania

Application May 12, 1934, Serial No. 725,284

8 Claims. (Cl. 66—127)

My invention relates to knitting machines, and particularly to mechanism for controlling the movements of the yarn carrier rods of straight or full fashioned knitting machines.

5 In any operation, where a selection of the number and position of the carrier rods to be operated is desired, and particularly, as for example, where, say three rods are to be reciprocated in predetermined sequence, while the 10 others, if there are others, are to remain stationary, a simple means for effecting such selection is highly desirable.

The above-recited example, of reciprocating three of the rods in sequence, has more recently 15 been extensively practiced in laying three yarns of like color, material and characteristics, in the knitting of a silk stocking, as distinguished from the more usual practice of knitting a stocking from one yarn supply. By knitting a stocking from a 20 plurality of yarn supplies sequentially in its several courses, a better average texture is obtained, free from the so-called "rings" or "shadows".

An object of the invention is, therefore, to 25 control the movements of the carriers in a simple, effective, accurate and certain manner, and to enable to be made a desired selection of the rods and the sequence of operation thereof for any purpose, particularly for a three-thread 30 fabric of the type above mentioned.

35 Another object of the invention is to provide selector mechanism for traversing a plurality of yarn carrier bars in predetermined sequence, comprising a device for locking the bars and selectively releasing them for actuation by the Coulier or other reciprocating mechanism, the device including rotary means adjacent to the locking means for direct engagement therewith, whereby to reduce the number of parts and simplify their form and operation. Preferably, and 40 as shown, the rotary lock release means rotates continuously in one direction to thus further simplify the parts, reduce the wear and the complication of movements of the elements and to 45 obtain other advantages.

Another object of the invention is to provide a 50 device of the above-indicated character that is simple and durable in construction, economical to manufacture, and effective in its operation.

55 With these and other objects in view, which will become apparent from the following detailed description of the illustrative embodiments of the invention shown in the accompanying drawings, my invention resides in the novel elements, mechanisms and combination of parts in co-

operative relationship, as hereinafter more particularly pointed out in the claims.

In the drawings:

Figure 1 is a fragmentary perspective view illustrating a plurality of carrier rods of a flat knitting machine as drawing individual threads from a plurality of yarn cones respectively; 5

Fig. 2 is a diagrammatic view illustrating one order or cycle in which three carriers are successively actuated to lay the threads respectively 10 controlled thereby to the needles of the knitting machine;

Fig. 3 is a longitudinally contracted plan view of sufficient of a flat knitting machine to illustrate the application of the mechanism of the 15 present invention thereto;

Fig. 4 is a transverse sectional elevation taken on the line 4—4, Fig. 3, showing the carrier-selecting mechanism in detail;

Fig. 5 is a front elevation as viewed in the direction of the arrow A in Fig. 4; 20

Fig. 6 is a detail view of certain cam members shown in Fig. 5;

Fig. 7 is a transverse sectional elevation taken on the line 7—7, Fig. 3, showing the ratchet 25 mechanism for intermittently rotating the carrier-selector shaft on which the selector cams are secured;

Fig. 8 is a plan view of the mechanism shown in Fig. 7; 30

Fig. 9 is a transverse sectional elevation taken on the line 9—9, Fig. 3, showing the mechanism for preventing over-running or rotary drifting of the selector shaft;

Fig. 10 is a longitudinal sectional elevation 35 taken on the line 10—10, Fig. 9;

Fig. 11 is a transverse sectional elevation taken on the line 11—11, Fig. 3, showing the carrier-locking mechanism, the carrier-releasing mechanism and the selector shaft ratchet operating 40 mechanism;

Figs. 12 and 13 are sectional elevations taken on the line 12—12, Fig. 11, showing the carrier-locking mechanism in different positions;

Fig. 14 is a transverse sectional elevation taken 45 on the line 14—14, Fig. 3, showing the synchronizing mechanism between the selector mechanism and the releasing mechanism;

Fig. 15 is a rear elevation of the synchronizing mechanism as viewed from the plane 15—15, 50 Fig. 3;

Fig. 16 is a sectional view taken on the line 16—16, Fig. 3;

Figs. 17 to 22, 17a to 22a and 17b to 22b diagrammatically illustrate the synchronization of 55

the carriers are carrier-releasing mechanism at the opposite ends of the machine during a complete cycle involving the laying of three individual threads successively to the needles of the machine for the formation of six courses of stitches by the needles.

Referring to the drawings, only the parts necessary to a full and complete understanding of the invention are therein shown, the various other parts and mechanisms, and the manner of operation thereof, being well known in the art, as shown and described in detail, in the "Reading" Full Fashioned Knitting Machine Catalogue, copyright 1929, and published by the Textile Machine Works, Reading, Pennsylvania.

In a full fashioned hosiery knitting machine, of the above-mentioned type, selected for illustrating the present invention, there are eight carrier bars, 1 to 8, inclusive, (see Figs. 3 and 4), 20 which are mounted in parallel laterally spaced relation to each other, for independent longitudinal reciprocation, in a plurality of relatively spaced carrier rod brackets 10 which are secured to the center bed beam 11 of the machine, said beam, in turn, being secured to the main center and end frames 12-12 thereof.

The carrier rods 1 to 8, inclusive, are adapted to be reciprocated by the usual "Coulier" motion of the machine through a longitudinally reciprocable slide rod 13 (see Fig. 4), on which is slidably mounted a series of usual friction boxes (not shown) and a special friction box 14, which may be operated as an ordinary box in the series for manual connection to, and release from, one of the carrier rods, and has special construction and operation, as hereinafter appears.

The present application, as a matter of illustration, involves the use of but three of the carrier rods, namely numbers 2, 3 and 5, for the sake of convenience.

As shown in Fig. 1, the carrier rods 2, 3 and 5, are provided with thread guides 2a, 3a and 5a, respectively. The thread guides 2a, 3a and 5a receive and control individual knitting threads 45 X¹, Y¹ and Z¹, respectively, which are drawn thereby from three separate yarn cones X, Y and Z, through the usual tensioning and moistening devices diagrammatically illustrated in Fig. 1.

The thread guides 2a, 3a and 5a are adapted 50 to lay their respective threads X¹, Y¹ and Z¹ to one and the same group of needles 15, (Fig. 1) in a predetermined order, each for knitting in the present case but a single course of stitches at any one time, and with no one of said threads being 55 served to the needles for the formation of another course of stitches until each of the other threads X¹, Y¹ or Z¹, as the case may be, has been knitted into a single course of stitches.

In the present case, the selection of the carrier rods in a definite predetermined order is effected 60 automatically. As a matter of illustration the three threads are arranged to be fed to the needles in the order X¹, Y¹, Z¹, which is repeated in corresponding cycles throughout the knitting 65 of the length of the fabric, each thread making but a single course of stitches in its turn in each cycle.

At the front of the machine, at substantially 70 the longitudinal center thereof, a selector mechanism is provided. This mechanism constitutes, in one aspect of the invention, an element thereof, in combination with other elements, but not being per se a part of the invention, only a sufficient description thereof is given herein for a

clear understanding of its operation in the combination. As part of this mechanism, the carrier rods 2, 3 and 5 are provided with actuating dogs 2b, 3b and 5b, respectively, by which these rods are adapted to be selectively and automatically connected to one of the friction boxes 14 by one or the other of a pair of connecting fingers 18 or 19, as the case may be, which are carried by a rod selecting rocker element 22.

The selector or rocker 22 is mounted for pivotal movement on and relative to the friction box 14, about the axis of a short shaft 26 which is secured in the selector and pivotally mounted in bearings 28, 28 formed on arms 29, 29 which extend laterally from one side of the friction box 14.

The arms 29, 29 are also provided with the second pair of bearings 30, 30 which encircle and are adapted to be moved longitudinally of a selector shaft 31, which latter extends parallel to the slide rod 13 and carrier rods 1 to 8, inclusive.

The shaft 31 is rotatably mounted in bearings 32, 32 which are carried by fixed brackets 36 secured to a suitable portion of the frame of the machine.

Adjacent to the bearings 30, 30 (see Fig. 5) is a pair of selector cams 41 and 42, respectively, each of which is provided with a sleeve-like hub 43 which is splined to the shaft 31 and is rotatably mounted in the bearing 30 adjacent to which the cam is positioned. Each sleeve hub 43 extends beyond the opposite side of the bearing at which its particular cam is located and is provided with a collar 44 secured thereto adjacent to its outer end, to prevent relative axial movement between the bearing and the cam, whereby, under longitudinal reciprocation of the friction box 14, said cams will be accordingly reciprocated relative to and on the selector shaft 31 during each stroke of reciprocation of the friction box 14 as it effects longitudinal movement of one of the carrier rods 2, 3 or 5, as the case may be, through the selector 22 and fingers 18 and 19 carried thereby, to lay the thread controlled by the guide thereon to the needles 15 of the machine for the formation of a single course of stitches.

At the end of each needle-traversing stroke of reciprocatory movement of the friction box 14, the selector shaft 31 is rotated, in the present instance through an angle of 60°, whereby the carrier rod previously moved by the friction box is released therefrom and whereby an operative connection is established between the friction box and another of the thread bars, depending upon the position to which the selector 22 on the friction box 14 is moved by the above noted partial rotation of the shaft 31.

The intermittent 60° rotations of the selector shaft 31 cause the cams 41 and 42 cooperatively to rock the selector 22 about its pivot, to release the connecting finger, 18 or 19 as the case may be, from the last operative carrier rod and to engage one of said fingers with the dog of the carrier rod next in turn to be actuated.

The selective rocking of the selector 22 by the cams 41 and 42 is effected through rollers 41a and 42a which are respectively engaged by the cams 41 and 42, said rollers 41a and 42a being rotatably mounted in angularly spaced relation to each other and to the axis of the pivot shaft 26, on the selector 22.

The intermittent 60° rotations of the selector shaft 31 are effected by mechanism shown in Figs. 7, 8 and 11. As shown in Figs. 7 and 8,

the selector shaft 31 has secured thereto a ratchet wheel 50. Pivotally mounted on the shaft 31 adjacent to the ratchet wheel 50 is a pawl carrier 51. Pivotally mounted at 52 on the pawl carrier 5 51 is a pawl 53 which is normally held in engagement with the ratchet wheel 50 by a spring 54 having one end secured to said pawl and its opposite end secured to the pawl carrier 51.

Pivotally attached at 55 to the pawl carrier 10 51 is one end of a link 56, the opposite end of which (see Fig. 11) is pivotally connected at 57 to one arm 58 of a lever 59, which latter is pivotally mounted at 60 on a bracket 61 secured to one of the main longitudinal beams 62 of the 15 machine. The second arm 63 of the lever 59 is provided with a cam follower in the form of a roller 64 which engages the peripheral edge of a cam 65 secured to the main cam shaft 66 of the machine.

20 As usual in full fashioned hosiery knitting machines, the main cam shaft 66 is adapted to be shogged axially to effect narrowing of the fabric by inwardly transferring groups of stitches adjacent to each of the selavage edges 25 of the fabric being knit on the bank of needles 15, during which time the thread carrier rods remain idle. In order to prevent disruption of the predetermined order in which the thread carriers are to be operated, in accordance with 30 the present invention, shogging of the shaft 66 moves the cam 65 from under the roller 64 and moves a substantially circular disc 67 into alignment with said roller, whereby rotation of the shaft 66, while effecting the above noted narrowing of the fabric, does not effect any intermittent rotation of the selector shaft 31.

Longitudinal movement of the carrier rods 1 to 8, inclusive, is limited by stops 70, 70 carried by the narrowing nuts 71, 71 at the opposite ends 40 of the machine, respectively (see Fig. 3), said narrowing nuts being moved inwardly in the usual manner in conjunction with the transferring of the stitches, as above referred to, by the usual narrowing screws 72 which are actuated 45 in the usual manner from the cam shaft 66 when said shaft is shogged axially to effect said narrowing.

As usual, the reciprocations of the friction box slide rod 13 are uniform and greater than the 50 maximum movement required by the friction box 14 to effect full needle-traversing movements of the carrier rods as determined by the positions of the stops 70 on the narrowing nuts 71, hence the carrier rods 1 to 8 engage the stops 55 70 and are stopped in their opposite longitudinal movements thereby. Such stopping of the carrier rods effects similar stopping of the friction box 14.

In order to prevent rebounding of the carrier 60 rods from the stops 70, each of the narrowing nuts 71 is provided with a guide bracket 73 for a pair of arresting levers 74 which cooperate with end abutments 75 of plates 76 which are 65 respectively carried by the carrier rods 1 to 8, inclusive. As the operating carrier rod is moved, for example in the direction of the arrow (see Fig. 12), to engage its stop 70 on the narrowing nut 71, one of the arresting levers 74 immediately drops behind one of the abutments 75 and 70 prevents rebounding of the rod when the same engages its respective stop 70.

When the rods are moved in the opposite direction, in the course of their reciprocation, the arresting levers 14, 74 are raised to clear the 75 top edges of the plates 76, to permit movement

of any one or all of the carrier rods at one time. The arresting levers 74 and the mechanism by which said levers are raised to permit the carrier rods to be moved, is standard equipment in this type of machine and detailed description thereof is deemed unnecessary. 5

In accordance with the principles of the present invention, each of the carrier rods 2, 3 and 5, in the present case, is individually locked against longitudinal movement except at such time as one of said rods is selected to lay its particular thread to the needles of the machine, and for this purpose each of the plates 76 on the carriers 2, 3 and 5 is provided with an inclined cam surface 77 and a notch 78 immediately behind the inclined surface 77 of said plate. 10 15

Secured to the narrowing nuts 71 intermediate the stops 70 and the guide bracket 73 for the arresting levers 74 are like housings 79 in one of which, at the left end of the machine, 20 are slidably mounted three spring-pressed plungers 80, 81 and 82 adapted to cooperate with and to lock the carrier bars 2, 3 and 5 respectively, said plungers each being beveled at its lower end, as indicated at 83, for engagement with the cam surface 77 on the carrier rod with which said plunger is associated to raise the plunger in the housing 79 against the action of its spring 84 as the carrier rod moves into the stop-engaging position shown in Fig. 12, said plunger immediately disengaging the rear edge of the incline 77 with a snap action into the notch 78 behind said inclined surface and thereby locking the carrier against movement in an opposite direction. 25 30 35

The locking plungers 80, 81 and 82 are adapted to be actuated to release the rods 2, 3 and 5 at such time as said rods are selected for movement by the selector 22 on the friction box 14. 40 There is a complete set of locking plungers at each end of the machine for holding the rods 2, 3 and 5 against accidental movement.

The locking plungers of the housing 79 at one end of the machine, for example the left end, which for future reference are identified as 80, 45 81 and 82, are adapted to be released by a series of pins constituting cam lobes 85, 86 and 87 and like cam plungers of the housing 79 at the opposite or right end of the machine, identified as 80a, 81a and 82a, are adapted to be released by a series of pins or cam lobes 85a, 86a and 87a, respectively. 50

The left end series of pins are rigidly mounted in, and project radially from, a cylinder 88 which is secured to a short shaft 89 carried by the bracket 73 which is secured to the narrowing nut 71 in the manner indicated in Fig. 11, and the pins 85a, 86a and 87a at the right end of the machine are similarly mounted in a cylinder 88a which is secured on a shaft 89a carried by the bracket 79a secured to the narrowing nut 71 at the said right hand end of the machine. 55 60 65

The shaft 89 for actuating the cylinder 88 and its cam lobes 85, 86 and 87 at the left hand end of the machine is actuated by a gear 90 secured thereto and meshing with a gear 91 which is splined to a releasing shaft 93 which extends across the back of the machine from end to end thereof, as shown in Fig. 3. The shaft 89a for actuating the cylinder 88a and its cam lobes 85a, 86a and 87a is actuated by a gear 90a secured thereto and meshing with a gear 91a which is also splined to the releasing shaft 93. 70 75

The releasing lobes 85, 86, 87 at the left end of the machine are disposed 120° apart at the one 75

end of the shaft 93, and the releasing lobes 85a, 86a and 87a at the opposite end of the shaft are arranged correspondingly in 120° spaced relation to each other, for actuating the plungers 80, 81, 82, 80a, 81a and 82a in predetermined 5 timed relation one to the other.

The releasing shaft 93, like the selector shaft 31, is adapted to be turned in intermittent steps of 60° and for the purpose of so operating the 10 shaft 93, in synchronization with the shaft 31, the shaft 31 is provided with a sprocket wheel 94 and the shaft 93 is provided with a sprocket wheel 95. Extending around the sprocket wheels 94 and 95 is a drive chain 96 (see Figs. 3, 14 15 and 15).

The gear 91 is mounted on, and splined to, the shaft 93 and is provided in its hub 92 with a circumferential groove for the reception of a forked arm 97 which is carried by the bracket 19, where- 20 by, as the narrowing nut 71 at the left hand end of the machine moves inwardly, the gear 91 is correspondingly moved axially along the shaft 93. The hub 92a of the gear 91a is similarly grooved for reception of a forked arm 97a, which 25 is carried by the bracket 19a associated with the narrowing nut 71 at the right hand end of the machine for movement therewith.

In order to prevent excess rotary movement of the shafts 31 and 93, the shaft 31 is provided 30 with a brake disc 98 mounted on one end thereof adjacent to and in contact with, a flat braking surface 99 formed on one of the brackets 36 by which the shaft 31 is supported, said brake disc 98 being pressed against the braking surface 99 35 by a convex spring disc 100 mounted on a squared portion 101 formed on one end of the shaft 31, the tensioning of the disc 100 being controlled by a pair of nuts 102 threaded on a reduced end 103 of the shaft 31.

40 The operation of the carrier rod locking and releasing mechanism forming the subject of the present invention, through a complete cycle involving the knitting of six interlooped courses of stitches by three different threads, will be fully 45 understood upon referring to the illustrations of Figs. 2, 17 to 22, 17a to 22a and 17b to 22b, in- clusive.

With the finger 18 of the selector 22 in contact with the dog 2b of the carrier rod 2, the 50 friction box 14 first moves to the right, as indicated by the arrows a in Figs. 2 and 17, respectively, until the right end of the carrier rod 2 engages its stop 70 at the right end of the machine. At such time, the rod 2 is locked, in the 55 manner above noted, by the plunger 80a (see Fig. 17b).

The shafts 31 and 93 are then synchronously 60 rotated to the extent of 60°, whereby the locking plunger 81a (see Fig. 18b) is actuated to release the carrier 3 and the selector 22 is rocked to move the finger 19 into engagement with the dog 3b on the rod 3.

The friction box 14 then moves to the left carrying the rod 3 in the direction of the arrow b 65 (Fig. 18) until said rod engages its stop 70 at the left end of the machine and the rod is engaged and locked against reverse movement by the locking plunger 81 (see Fig. 18a).

The shafts 31 and 93 are then again rotated 70 to the extent of 60°, whereby the finger 19 of the selector 22 is moved into engagement with the dog 5b of the rod 5. At the same time, the plunger 82 (see Fig. 19a) is actuated to release the rod 5.

75 The friction box 14 then moves to the right,

carrying the rod 5 in the direction of the arrow c (Fig. 19), until said rod engages its stop 70 at the right end of the machine and is engaged and locked by the plunger 82a (see Fig. 19b).

The shafts 31 and 93 are then again rotated to 5 the extent of 60°, whereby the finger 18 of the selector 22 is brought into engagement with the dog 2b of the rod 2. At the same time, the plunger 80a (see Fig. 20b) is actuated to release the rod 2.

The friction box 14 then moves to the left carrying the rod 2 in the direction of the arrow d (see Fig. 20), until said rod engages its stop 70 at the left end of the machine and is engaged and locked by the plunger 80 (Fig. 20a).

The shafts 31 and 93 are then rotated 60°, causing the finger 19 to be moved into engagement with the dog 3b of the rod 3, and the plunger 81 is actuated to release the rod 3 (Fig. 21a), after which, movement of the friction box 14 to 20 the right carries the rod 3 in the direction of the arrow e, (Fig. 21), until said rod engages its stop 70 at the right end of the machine and is engaged and locked by the plunger 81a, (Fig. 21b).

The shafts 31 and 93 then move another 60° causing the finger 19 to move into engagement with the dog 5b of the rod 5, the plunger 82a (see Fig. 22b) at the same time being operated 30 to release the rod 5.

The next movement of the friction box 14 to the left carries the rod 5 in the direction of the arrow f (Fig. 22), until said rod engages its stop 70 at the left end of the machine and is engaged and locked by the plunger 82 (Fig. 22a).

The shafts 31 and 93 are then rotated to the extent of 60° causing the finger 18 of the selector 22 to be engaged with the dog 2b of the rod 2, at the same time causing the plunger 80 (see Fig. 17a) to release said rod 2 for the beginning of a 40 repeat of the cycle as just described.

The 60° rotations of the shafts 31 and 93 synchronously rotate the cams 41 and 42 and the cylinders 88 and 88a; such actuations of the cams 41 and 42 effecting the selection of the rod 45 to be actuated by the friction box 14 by rocking the selector 22 into the proper position to place one or the other of the selector fingers 18 or 19 in proper engagement with the dog 2b, 3b or 5b of the rods 2, 3 and 5, respectively; and the 50 simultaneous actuation of the cams of the cylinders 88 and 88a with the pins 85, 86, 87, 85a, 86a and 87a thereon effecting release of the selected rod by lifting the locking plunger 80, 81, 82, 80a, 81a or 82a, as the case may be, out of the locking 55 notch 78 in the selected rod.

The locking plungers 80, 81, 82, 80a, 81a and 82a are, respectively, provided with laterally extending shoulders 110 (see Figs. 12 and 13) which 60 overhang the path of rotary movement of the pins or cam lobes 85, 86, 87, 85a, 86a and 87a, respectively, and the arrangements of the pins on and around the cylinders 88 and 88a collectively is such that, as these two cylinders are rotated simultaneously and in invariable relation to each other, the pins thereon will engage the shoulders on the plungers in the same successive order in which the selector 22 effects driving connections between the friction box 14 and the carrier rods 2, 3 and 5, respectively.

Of course, the improvements specifically shown and described, by which I obtain the above results, can be changed and modified in various ways without departing from the scope of the in- 75

vention herein disclosed and hereinafter claimed.

I claim:

1. In a flat knitting machine, a cam shaft, a series of parallel independently reciprocable 5 yarn-carrier rods, carriages adjacent to opposite ends, respectively, of the rods movable toward and away from each other parallel to the rods, a series of locking elements mounted on each carriage and slidable relative thereto perpendicularly to the rods for controlling the reciprocations of the rods, rotary means mounted on the carriages including elements for selectively releasing the locking means from the rods, a control shaft extending parallel to the rods, means 10 operatively connecting the control shaft to each rotary means, and means for maintaining the operative connection between the control shaft and the rotary means irrespective of said movement of the carriages toward and away from 15 each other.

2. In a flat knitting machine, a cam shaft, a plurality of yarn-carrier rods, means for reciprocating the rods, means for selectively connecting the rods to the reciprocating means, carriages adjacent to the opposite ends, respectively, of the rods and movable toward and away from each other parallel to the rods, means on the carriages for limiting the extent of reciprocation of the rods and locking each rod independently of the others against reciprocation relative to the carriages, rotary means mounted on the carriages including elements for selectively controlling the locking means to lock and release the rods, means on the carriages for actuating the rotary means, means for synchronizing the rotation of the rotary means with each other including a control shaft extending parallel to the rods and connected to the actuating means on each carriage, and means for rotating 40 the control shaft.

3. In a flat knitting machine, a cam shaft, a plurality of yarn-carrier rods, means for longitudinally reciprocating the rods, means for selectively connecting the rods to, and releasing them from, the reciprocating means, rotary means for actuating the selective connecting means, carriages adjacent to the opposite ends of the rods and movable toward and away from each other parallel to the rods, means on the carriages for limiting the extent of reciprocation of the rods and locking each rod independently of the others against reciprocation relative to the carriages, rotary means on the carriages including elements for selectively controlling the locking means to lock and release the rods, means for synchronizing said rotary actuating means with said rotary control means including a control shaft extending parallel to the rods, means operatively connecting the rotary actuating means to the control shaft, and means operatively connecting the rotary control means to the control shaft and maintaining the connection irrespective of said movement of the carriages toward and away from each other.

4. The combination of a series of substantially parallel independently reciprocable thread bars, variable means at the opposite ends of said bars respectively for limiting said reciprocations thereof, a series of perpendicularly slidable locking elements carried by each of said variable means for said bars respectively, a laterally extending shoulder on each locking element, a shaft rotatably mounted on each of said variable means and extending transversely of said bars, a cylinder on each of said shafts adjacent said locking

elements, projections on each of said cylinders respectively engageable with the shoulders on said locking elements for independently releasing said elements from said bars, an actuating shaft rotatably mounted in parallel relation to said bars, a gear on each cylinder shaft intermeshing with a gear splined to said actuating shaft, and means carried by said variable means for sliding said splined gears on said actuating shaft.

5. The combination of a series of substantially parallel independently reciprocable thread bars, variable means at the opposite ends of said bars respectively for limiting said reciprocations thereof, a series of perpendicularly slidable locking elements carried by each of said variable means for said bars respectively, a laterally extending shoulder on each locking element, a shaft rotatably mounted on each of said variable means and extending transversely of said bars, a cylinder on each of said shafts adjacent said locking elements, projections on each of said cylinders respectively engageable with the shoulders on said locking elements for independently releasing said elements from said bars, an actuating shaft rotatably mounted in parallel relation to said bars, a gear on each cylinder shaft intermeshing with a gear splined to said actuating shaft, means carried by said variable means for sliding said splined gears on said actuating shaft, and means for intermittently rotating said actuating shaft.

6. In a flat knitting machine comprising a plurality of thread bars, means for reciprocating said bars, means for selectively connecting said bars to said reciprocating means, variable means adjacent the opposite ends respectively of said machine and movable toward and away from each other for limiting the extent of the reciprocations of said bars, means carried by said variable means for locking each bar independently against reciprocation relative to said variable means, a rotary cylinder carried by the variable means adjacent the locking means thereon at each end of the machine, a plurality of pins carried by each cylinder for selectively releasing said bars from the locking means at such ends of the machine, means carried by each of said variable means for rotating the cylinder thereon, means for synchronizing the actuations of the cylinders at the opposite ends respectively of said machine, including a control shaft extending from end to end of said machine and to which the cylinder rotating means on said variable means are respectively splined, and means for rotating said shaft.

7. In a flat knitting machine comprising a plurality of thread bars, means for reciprocating said bars, means for selectively connecting said bars to said reciprocating means, variable means adjacent the opposite ends respectively of said machine and movable toward and away from each other for limiting the extent of the reciprocations of said bars, means carried by said variable means for locking each bar independently against reciprocation relative to said variable means, a rotary cylinder carried by the variable means adjacent the locking means thereon at each end of the machine, a plurality of pins carried by each cylinder for selectively releasing said bars from the locking means at such ends of the machine, means carried by each of said variable means for rotating the cylinder thereon, a shaft rotatably mounted on each of said variable means and to which the cylinders thereon are

- respectively secured, a common drive shaft extending from end to end of the machine for driving said cylinder shafts, a beveled gear on each cylinder shaft and an intermeshing beveled gear on and splined to said common drive shaft for movement thereon in accordance with the movements of said variable means at each end of the machine.
8. In a flat knitting machine comprising a plurality of thread bars, means for reciprocating said bars, means for selectively connecting said bars to said reciprocating means, variable means adjacent the opposite ends respectively of said machine and movable toward and away from each other for limiting the extent of the reciprocations of said bars, means carried by said variable means for locking each bar independently against reciprocation relative to said variable means, a rotary cylinder carried by the variable means adjacent the locking means thereon at each end of the machine, a plurality of pins car-

ried by each cylinder for selectively releasing said bars from the locking means at such ends of the machine, means carried by each of said variable means for rotating the cylinder thereon, a shaft rotatably mounted on each of said variable means and to which the cylinders thereon are respectively secured, a common drive shaft extending from end to end of the machine for driving said cylinder shafts, a beveled gear on each cylinder shaft and an intermeshing beveled gear on and splined to said common drive shaft for movement thereon in accordance with the movements of said variable means at each end of the machine, and a forked arm carried by each of said variable means and operating in a groove in the splined gear adjacent thereto for assuring movement of the gear on the common drive shaft in accordance with the movement of said variable means.
